CONTROL MECHANISM FOR ARTIFICIAL LEGS

Emil George Haag, Inglewood, Calif.

Application November 19, 1947, Serial No. 786,851

3 Claims. (Cl. 3—27)

1

This invention relates to control mechanism for artificial legs and particularly to the type used when the amputation is above the knee.

The primary object of my invention is the provision of a hydraulic mechanism to be installed inside of an artificial leg, that will prevent the collapse of the leg when bending the knee or when the foot strikes obstructions on the pavement, such as twigs, stones or the like.

Another object is the provision of a mechanism that will allow the user of an artificial leg to have full control over the leg at all times so that he may walk with the same ease equal to a natural leg, and wherein there is avoided danger of falling due to failure of the leg to stay rigid when stepping on obstacles or uneven pavements.

A further object is the provision of a hydraulic mechanism for use in artificial legs, adapted for use when the amputation is above the knee, which is controlled by a lever in the artificial foot, affording the user full controlled action of the mechanism, to bend the knee and to kick same in position automatically when the user puts his weight on the leg while walking or standing.

The invention will be best understood from a consideration of the following detailed description taken in connection with the accompanying drawings forming a part of the specification, with the understanding, however, that the invention is not to be understood as limited to the exact details of construction shown and described since obvious modifications will occur to a person skilled in the art.

In the drawings:

Figure 1 is a full front elevation of an artificial leg constructed in accordance with one embodiment of my invention.

Figure 2 is a longitudinal section taken substantially on line 2—2 of Figure 1, and showing the mechanism in relative position to an artificial leg as shown in broken outline.

Figure 3 is a view in side elevation of a second embodiment of my invention.

Figure 4 is a fragmentary longitudinal section of the stop valve and piston structure of the embodiment of Figure 3, assembled in one housing.

Figure 5 is a sectional view taken substantially on the line 5—5 of Figure 2.

Referring particularly to Figures 1, 2 and 5 wherein one embodiment of the invention is illustrated it will be noted particularly in Figures 1 and 2 that the device employs the transverse toe, heel, knee and thigh pins which are indicated respectively by the reference characters 11, 12,

2

13 and 14 and these pins function to secure the mechanism in an artificial leg structure which is shown in broken outline and designated 10, such leg structure being of suitable flexible construction to permit the operation of the mechanism.

The toe pin 11 extends transversely of and connects together the forward ends of the spaced parallel foot bars 15 which are disposed between and are pivotally mounted for vertical oscillation or swinging, upon the heel pin 12 which couples together the lower ends of the spaced parallel calf bars 16. As shown the lower ends of these calf bars are curved to extend rearwardly slightly, such curved portions being designated 16' so that the heel pin 12 is rearwardly of the plane of the bars 16.

Extending transversely between and connecting the foot bars 15 adjacent to but in advance of the heel pin 12, is a cross pin 17 which lies in the vertical plane of the spaced calf bars 16.

The cross pin 17 is engaged by the lower end of the stem or rod 18 of a diaphragm type pump which is generally designated 19 and which is mounted between the lower ends of the calf bars as shown in Figure 1. The stem 18 of this diaphragm pump is normally urged downwardly by the coil spring 42 so that the diaphragm pump stem or rod 18 constantly engages the pin 17 so as to urge the toe of the artificial leg downwardly at all times.

The numeral 20 generally designates a stop cylinder assembly which comprises a piston cylinder 20' mounted upon a supporting pin 21 which is secured to and extends across between the calf bars 16 above the diaphragm foot pump 19. The cylinder is maintained centrally between the calf bars by the spacers 22.

Slidably positioned within the cylinder is a piston 23 to which is fixed the piston rod 24 which extends upwardly beyond the upper ends of the calf bars 16 and is pivotally coupled at its upper end with a cross pin 25.

The numeral 26 designates two spaced parallel thigh bars which at their lower ends are of increased width as indicated at 26' and the forward ends of the portions 26' of the thigh bars have therein the elliptical openings 27 through which the knee pin 13 passes. This pin 13 is rigid with the upper end of the calf bars 16 but is adapted to have slight vertical movement in the elliptical openings 27 of the thigh bars so that the calf portion of the artificial leg may move up and down slightly for the correct operation of the mechanism.

Between the upper ends of the calf bars 15 is a spacer sleeve 28 which encircles the knee pin 13.

At the rear of each of the thigh bar lower end portions 26' there is mounted upon a pivot 31 a short forwardly extending lever 30 which overlies and rests upon the top of the spacer sleeve 28.

Disposed between the lower ends of the thigh bars 26 is an inverted substantially U-shaped yoke 32, the legs of which are in spaced parallel relation with the thigh bars 26 and the lower end of each leg of this yoke is pivotally secured as at 33 to a lever 30. Each of the side portions or legs of the yoke 32 has a slot formed longitudinally therein as indicated at 34 through which the cross pin 25 of the piston rod freely passes so that the yoke is permitted free limited movement independently of the pin 25.

Supported between the thigh bars 26 above the yoke 32 is a stop regulating valve 29 which comprises a body 29' in which is formed a cylindrical chamber *a* which opens through the lower end of the body toward the yoke 32. Slidably mounted in this chamber *a* is a plunger 35 which is secured at its outer end to the yoke 32 and carries upon its inner end the valve needle *b* which when advanced in the cylinder by the upward movement of the yoke 32 engages the conical seat *c* to close the valve.

A compression spring *d*, within the valve chamber *a*, normally resists inward movement of the plunger 35 and tends constantly to move the plunger and the yoke outwardly.

The numeral 36 designates a fluid tank which is supported upon the forward sides of the thigh bars 26 and leading downwardly from this tank is the feed line 37 which supplies the diaphragm foot pump 19 with fluid through the downwardly opening check valve 38. This tank is at all times substantially filled with fluid.

Leading upwardly from the tank or receptacle 36 is a pipe line 39 which opens at its upper end into the chamber *a* below the needle valve seat *c*. Leading from the outlet side of the diaphragm pump 19 to and opening into the lower end of the cylinder 20' is the pressure pipe line 40. The passage of fluid through this pipe line 40 is controlled by the upwardly opening check valve 40' which permits fluid to pass only from the diaphragm pump into the lower end of the piston cylinder 20'.

Also communicating with the lower part of the piston cylinder 20' is an end of an exhaust pipe line 41 which discharges into the chamber *a* of the stop valve 29 above the needle valve seat *c* or, in other words, upon the opposite side of the seat from the point where the pipe 39 opens into the valve chamber.

It will be understood that since there must be relative movement between the knee pin 13 and the thigh bars 26, as provided for by the elongated or elliptical openings 27, the body of the artificial leg 10 must also have elongated openings to receive the outer ends of the knee pin 13 to permit such relative movement between the thigh bars and the calf bars.

When the foot is lifted the lower part of the leg moves downwardly, that is, the calf bars and all of the parts connected therewith shift down away from the thigh bars. This permits downward movement of the yoke 32, assisted by the spring *d*, together with the plunger 35 and the levers 30 thus opening the needle valve to establish a clear passage between the tubes 39 and 41. The free bending of the knee is then permitted

and the discharge of fluid from the lower part of the cylinder 20' by the downward movement of the piston 23 under such bending of the knee, will take place into the line 41 from which it will pass through the open valve 29 to the line 39 and to the tank 36.

When the user puts weight on the leg, the oblong or elliptical holes 27 permit the lower part of the leg mechanism to shift upwardly which 10 action raises the levers 30 together with the yoke 32 and effects the closing of the valve 29 by the introduction of the valve needle *b* into the seat *c*. Consequently when pressure is applied to the leg structure, no fluid can move from the cylinder 20' and the cylinder and piston form a rigid coupling across the knee joint to lock the joint. The user of the device may then rest his full weight on the artificial leg without fear of it collapsing. It will also be seen that the diaphragm pump will function under the application of weight to the artificial leg to assist in straightening and holding the leg rigid by reason of the fact that when the foot bars 15 are swung upwardly to force the diaphragm pump rod 18 in, 20 fluid will be ejected from the diaphragm pump through the check valve 40' and into the lower end of the piston cylinder 20' thereby tending to force the piston 23 outwardly.

The foot pump 19 is employed as a booster to 30 help straighten out the leg when the user is in a sitting position. This position brings the stop piston 23 to its lowest position in the cylinder which makes it difficult for the user to easily straighten out the leg without assistance. By 35 using the foot pump the user, when wishing to rise from a sitting position to a standing position, puts weight on the foot bars 15 which actuates the diaphragm pump rod 18 and causes fluid to be ejected from the diaphragm pump into the cylinder 20' to force the piston outwardly. 40 By repeating the pressure on the foot bars 15 the diaphragm pump will continue to draw fluid from the line 37 and force it into the cylinder 20' until the leg is entirely straightened out and the user may then apply his full weight without fear of the leg bending or collapsing since any downward motion of the piston 23 will be prevented due to the fact that the valve 29 will be closed and the fluid cannot escape from the cylinder 20'.

To facilitate the free bending of the leg when the user desires to sit down there is provided the fluid shunt line 41' across the valve 29. In this shunt line is located a valve 41'a which is manually controlled by the user through the medium of a flexible cable 41'b. This valve 41'a and its flexible control cable are of well known standard construction and accordingly it is believed that a detailed illustration and description of the same are not required. It will be seen that when the user is standing and wishes to sit the valve 29 will be closed because of the pressure applied to the calf bars 16. By opening the valve 41'a communication is established between the lines 41 and 39 across the valve 29 and the user may then bend his leg in order to be seated, the fluid ejected from the cylinder 20' by this operation passing back to the tank or receptacle 36 as will be readily apparent.

The embodiment of the invention thus far described is for use in those cases where the amputation is high above the knee.

For cases in which the amputation is at or just slightly above the knee the embodiment illustrated in Figures 3 and 4 may be employed, the

construction here being such that the high bars can be made considerably shorter.

It will be readily apparent that this second embodiment of the invention will be mounted within an artificial leg in substantially the same manner as the first described embodiment, use being made for this purpose of the transverse pins 11a, 12a, 13a. Foot bars 15a are mounted for vertical oscillation on the pin 12a and the lower ends of the calf bars 16a are rearwardly curved as indicated at 16b whereby to properly position the connecting pin 17a for engagement by the pump rod 18a of the diaphragm pump 19a. At the upper ends of the calf bars 16a the forwardly curving lower ends of the thigh bars 26a position between the calf bars 16a and are pivotally mounted upon the pin 13a.

In this embodiment the stop cylinder and the stop regulating valve are assembled as a unit which is generally designated 20a and is mounted between the calf bars 16a upon the supporting pin 21a. This unit is formed to provide the piston cylinder 43 which opens upwardly to receive the piston 23a, the upper end of which is pivotally coupled with the pin 25a which connects across between the thigh bars 26a.

Also formed in the unitary body 20a is a chamber 55 which is adjacent to and parallels the piston cylinder 43 and in which chamber 55 is slidably mounted the needle valve piston 45 which carries the upper and lower needle valves 46 and 47 respectively on the ends of the upwardly and downwardly extending stems 46a and 47a.

Paralleling the cylinder 43 is a fluid passage 57, the lower end of which communicates with the lower end of the cylinder as shown and also communicates with the passage 54 which leads upwardly into the chamber 54a into which the valve needle 47 moves in opening. The upper end of the passage 57 communicates with the port 46b which is closed by the upper needle valve 46 when it moves upwardly or to closing position.

Housed in the chamber 55 above the valve piston 45, is a spring 56 which engages the piston 45 and normally urges the same downwardly thus constantly tending to move the valve needle 46 to open position and the valve 47 to closed position.

The fluid tank or receptacle 36a is mounted upon the thigh bars 26a and the lower part of this tank has connected therewith the tube 49 which opens into the upper part of the chamber 55 above the valve piston 45 but below the inlet port 46b. From the lower part of the chamber 55, below the valve piston 45, an end of a tube 48 leads downwardly to the outlet side of the diaphragm pump 19a. This tube has therein the upwardly opening check valve 48a which permits fluid to pass only from the diaphragm pump upwardly and into the lower part of the piston chamber 55.

The tube 48 is also in communication with the chamber 54a with which the passage 57 is in communication when the valve needle 47 is raised or in open position, this communication between the chamber 54a and the tube 48 being by means of the connecting nipple 54b.

Connected at one end with the upper part of the tank 36a is the fluid suction line 50 which leads downwardly and opens at its opposite end into the other side of the diaphragm pump 19a through a downwardly opening check valve 50a. Above the check valve 50a a coupling nipple 50b leads from the pipe line or tube 50 into the lower part of the stop cylinder 43 and above this nip-

ple the pipe line 50 has a downwardly opening check valve 51 therein.

Connecting the upper end of the tube 48 with the lower end of the tube 49 is a valve shunt tube 52 in which is located a valve 53 of the same type as the valve 41a, to be manually controlled by the user of the mechanism to facilitate bending the artificial leg at the knee when the wearer desires to sit down. The numeral 53a designates the flexible control cable by which the manual valve 53 is actuated.

While the mechanism is slightly different in this second embodiment of the invention the operation of the same is essentially the same as that of the first embodiment, such operation being, however, entirely through the medium of the foot bars 15a.

The valve 53 is normally closed and when pressure is applied to the foot bars 15a the diaphragm 20 of the pump 19a will be compressed to eject fluid upwardly through the tube 48 into the chamber 55 below the valve piston 45 thus raising the piston and closing the port 46b by means of the valve 46. This will open the valve needle leading to the passage 54 and fluid may pass into the lower part of the piston cylinder 43. It will thus be seen that full weight may be applied upon the mechanism since downward pressure to the piston 23a in the cylinder 43 will fail to 30 eject any fluid from the cylinder due to the fact that the port 46 is closed. Thus desired upward thrust will be applied to the thigh bars 26a and the knee joint will be locked.

When the user of the mechanism desires to 35 sit down thus requiring the release of the piston 23a so that the thigh bars 26a can swing down on the pivot pin 13a, the control valve 53 is opened thus permitting the fluid to pass from the cylinder 43 through the passage 54 into the 40 upper end of the pipe line 48 and then through the shunt line 52 to the line 49 which returns the fluid to the tank 36a.

After the user of the mechanism has taken a 45 step to thereby lock the piston 23a in its raised position, when the leg is lifted the fluid in the cylinder 43 passes out into the lower part of the suction line 50, flowing back to the pump 19a. This flow takes place as a result of the action 50 of the spring 18a forcing the foot bars 15a downwardly thus relieving the pressure upon the diaphragm of the pump 19a and creating a reduced pressure in the pump chamber. The movement 55 of the fluid out of the cylinder 43 reduces the fluid pressure by way of the nipple 54b and the passage 54, in the lower part of the chamber 55 beneath the valve piston 54 thus allowing the needle valve 46 to open. The knee joint is now free to function for the bending of the leg and downward movement of the piston 23a will cause 60 the fluid to pass back to the tank 36a by way of the passage 57 and the port 46b. When the foot is again placed on the ground and the foot bars 15a are forced upwardly the same locking action 65 of the piston 23a will occur and these actions will continue to alternate during the walking movements of the wearer.

It will be seen from the foregoing that the mechanism of the present invention as illustrated in the two embodiments shown, is of relatively 70 simple character and will function smoothly and rapidly to permit the amputee to walk, stand or sit down or execute other movements of the leg which are permitted with the normal leg. At the same time there are no small, delicate parts to 75 get out of adjustment or parts requiring frequent

adjustment for the proper operation of the device.

I claim:

1. An artificial leg control mechanism designed for installation in an artificial leg body, comprising a thigh portion, a knee joint pin carried by the thigh portion, a relatively long calf portion pivotally mounted at one end upon said pin, an ankle pin carried at the other end of the calf portion, a foot part pivotally mounted upon said ankle pin, said knee joint pin and thigh portion being loosely coupled together to form a lost motion joint between the thigh and calf portions whereby the calf portion has a slight free rectilinear movement relative to the thigh portion, a brace element connected between the thigh and calf portions across the knee joint, said brace element comprising a fluid cylinder, a piston in the cylinder and a piston rod extending outwardly from the cylinder, a fluid receptacle carried by one of said portions, means for conducting fluid from the receptacle into said cylinder beneath the piston, a fluid line leading from the cylinder from beneath the piston back to the receptacle, valve means carried by the thigh portion for closing said fluid line, and an operative coupling between said valve means and the calf portion operating to close the valve means upon rectilinear movement of the calf portion in one direction.

2. An artificial leg control mechanism of the

character stated in claim 1, wherein the said means for transferring fluid from the receptacle to the cylinder beneath the piston includes a pump carried by a portion of the mechanism, and an operative coupling between the pump and the foot portion for effecting the operation of the pump upon actuation of the foot portion on the ankle joint pin.

3. An artificial leg control mechanism of the character stated in claim 1, wherein the said means for transferring fluid from the receptacle to the cylinder beneath the piston includes a pump carried by a portion of the mechanism, and an operative coupling between the pump and the foot portion for effecting the operation of the pump upon actuation of the foot portion on the ankle joint pin, a fluid shunt line connected across the valve in the line leading from the piston cylinder back to the receptacle, and a manually-controlled valve in the fluid shunt line.
